UNITED STATES PATENT OFFICE

HARRY E. WOLF, OF PITTSBURGH, PENNSYLVANIA

TUFTING TABLE APPARATUS

Application filed May 31, 1930. Serial No. 458,744.

My invention relates to the art of mattress making, and it has special reference to tufting tables proper, and needle devices for use in conjunction with such tables for tufting mattresses.

One object of my invention is to provide a tufting table having a perforated bottom member and a removable top member, with relatively small openings, substantially aligned with the respective perforations in the bottom member, together with a needle device adapted to be successively guided by said openings through the respective perforations, in order to produce symmetrical and neat tufting of a mattress.

A second object of my invention is to provide a tufting table, having a top and bottom member for enclosing the mattress being worked upon, that may be rotated with respect to an upright frame, and the parts locked in position, irrespective of whether the apparatus occupies its normal or its inverted position.

Another object of my invention is to provide a table of the character set forth, so arranged that the centers of the openings in the top and bottom members may substantially exactly register each time that the apparatus is assembled.

A further object of my invention is to provide a tufting needle device, having a slideable guide block, to insure rapid and accurate tufting of the mattress being worked upon, when the tufting device is utilized in conjunction with my table.

Still another object of my invention is to provide a tufting needle device, wherein a plurality of removable members are so located upon a guide block for the needles, as to insure close or accurate guiding thereof, and at the same time, to facilitate disassembly and repair in the event of a breakdown.

Other objects of my invention will become evident from the following detailed description, taken in conjunction with the accompanying drawings, wherein,

Figure 1 is a view, in side elevation, of a tufting table organized in accordance with my present invention,

Figure 2 and Figure 3 are views, in top

plan and in side elevation, respectively, of the apparatus shown in Figure 1, and

Figure 4 and Figure 5 are views, in side elevation and in bottom plan, respectively, of my tufting needle device.

Referring to Figures 1, 2 and 3 of the drawings, the tufting table here shown comprises a pair of transverse frame members 1, which may constitute standard T-irons and which are respectively supported on pairs of legs 2, which may be formed of channel irons, for example. A bottom table member proper 8, and an upper table member 13, interlock with each other and are pivotally supported on the frame members 1, being capable of being locked in position by means of suitable pivot locks 6.

The transverse frame members 1 may be secured by means of bolts 3, to the legs 2, which in turn, may be secured to the floor by small angle irons 4, bolted to the lower ends of the legs.

Hubs or bearings 5 are bolted to the middle portion of each of the transverse frame members 1, for the purpose of providing a pivotal bearing for the lower table member 8. Preferably, the illustrated pivot pin extends a short distance into the bottom table member 8, being suitably reinforced by means of plates 5a. By reason of this pivotal connection, the table member 8 and its associated parts, namely, the top table member 13, and the intervening mattress 25 being worked upon, may be readily rotated from its normal to its inverted position by a light touch of the hand.

To insure that the table members are locked in position when it is desired to work upon the mattress, a pair of the pivot locks 6 are mounted, by means of pivot pins or bolts 7, on each of the transverse frame members 1, about half way between the bearing 5 and the ends of the frame member. Each of these pivot locks is provided with a suitable handle 6a, and the inner end is bifurcated to grip the bottom member 8 in either a normal or an inverted position, as the case may be, and thus hold the rotatable table assembly in the desired operative position. For the purpose of preventing undue wear, by

100

the use of these pivot locks, reinforcing plates 10 are preferably secured to the bottom table member 8, in the positions where the bifurcated inner ends of the pivot locks engage the bottom table member.

5 The bottom table member 8 is made from any suitable material, such as wood, the inner face being provided with a suitable veneer 9. Similarly, the inner face of the top table member 13 is provided with a suitable veneer 14. The bottom member 8 has a number of relatively large holes 12, drilled through it for the purpose of permitting tying of tufting material to form a tuft, after the tapes 13 or other material have been threaded through, as subsequently described.

10 The top member 13, on the other hand, is provided with an equal number of relatively small openings or slots 21, having a circular or enlarged center, for a purpose to be hereinafter set forth. The registration of the centers of each of the small slots or openings in the top member with the centers of the large openings in the bottom member, is insured 15 by means of suitable male and female centering posts 11 and 20. A pipe or hollow post 11 is secured to each corner of the upper side of the bottom plate member 8, and a pin or solid post 20 is secured to each corner of the 20 lower face of the upper table member 13. These pins and hollow posts are adapted to engage when the top and bottom members are in operative position, whereby the desired registration of the openings in the top and 25 bottom table members is readily effected each time the apparatus is being used.

30 The top table member 13 is provided with reinforcing metallic strips or the like 15, at the ends thereof on the upper side, and a plurality of cables 16, are secured to screw eyes 16a in each of the plates 15, at the corners, the four cables being joined at the center to a hook 17, and a single cable passing from the hook over a pulley 18, which is suitably 35 attached to the ceiling or other support (not shown). The purpose of this arrangement is to permit the top table member 13 being readily raised when the mattress is being laid on the bottom table member 8, or taken off it, 40 and also to permit readily placing the top table member on the mattress and effecting the proper positioning of the member 13, by means of the centering posts 11 and 20.

45 For the purpose of holding the top and bottom table members in suitable position with respect to the mattress 25, a plurality of clamps 26 are passed over the sides of the top and bottom table members, at suitable intervals, thereby compressing the mattress 50 to the desired thickness, and placing the entire apparatus in the best possible condition to insure rigid, accurate and neat workmanship in threading the tufting needles therethrough.

55 The tufting needle device shown in Figure

4 and Figure 5, comprises a pair of long needles 27 and 28, having enlarged points or heads 36 and 37, in back of which eyes 38 are provided, through which the usual tape may be threaded. The upper or blunt ends of these needles are engaged in a hand grip 29, of any suitable form, and a guide block 30, having outer ridges or legs 39 and 40, loosely engages the needles 27 and 28 back of or above the eyes 38.

60 For the purpose of permitting the hand grip 29 to slide toward the block 30, and advance the needles 27 and 28 through the mattress, a pair of guides or rods 31 are provided, being rigidly secured at their lower ends to metallic or other members 32, by means of suitable pairs of nuts 33. The plates 32 are secured by screws 50 to the upper side of block 30. The upper ends of the rods 31 pass through a metallic or other plate 34, secured to the lower side of the hand grip 29, and nuts 35 are secured to the rods 31 on the opposite side of the plate 34, whereby the hand grip 29 may be slid up and down the rods 31 toward the guide block 30, and carry the needles 27 and 28 with it.

65 For the purpose of suitably guiding the needles 27 and 28 in their downward passage, and at the same time facilitating disassembly and repair of the needle device, a plurality of square plates 41, 42 and 43 are placed in juxtaposition, or adjacent to each other, being secured to the underside of the guide block 30, in a groove formed between the legs 39 and 40, by means of a plurality of screws 44. Thus the intermediate plate 42 lies between the two needles 27 and 28, while the plate 41 is on the outer side of the needle 27 and the plate 43 is on the outer side of the needle 28. The portion of each plate 41, 42 and 43, adjacent to the respective needles, is notched or cut, as indicated at 45 (Fig. 5), whereby a smooth, close or accurate guide or passage for each needle is provided, and the openings through the guide block 30 need not be closely fitted to the needles, but may provide a suitably loose passage therefor.

70 Similarly, a small plate 51 may be provided on the upper side of the guide block 30, between the needles 27 and 28, while the plates 32, to which the rods 31 are rigidly secured, are located on the outer sides of the needles 27 and 28, these three plates being notched similarly to the lower plates 41, 42 and 43, for the same purpose of closely guiding the needles. The plates 32 and 51 may be suitably secured to the guiding block 30 by means of screws 50, or otherwise.

75 By reason of the construction just described, in the event that one of the needles 27 or 28 breaks, it is not necessary to disassemble the entire tufting device, in order to replace a needle, but merely the adjacent plates, such as 41 and 42, 32 (left hand) and 51, in the event that needle 27 is broken.

These plates may be quickly removed, inasmuch as only a single fastening member or screw holds each plate, whereupon the broken needle may be quickly withdrawn and a proper replacement made. Thus, the needles are accurately guided by means of closely fitting members, thereby insuring accuracy and minimum wear in the operation of the needles, and in addition, replacements may be quickly and easily made.

10 Assuming that the top table member 13 occupies its suspended position near the ceiling, and that the bottom table member 8 occupies the position shown in the right hand side of Figure 2, with the pivot locks 6 in the illustrated locked position, the operation of the apparatus may be set forth as follows:

15 The mattress 25 to be worked upon, is laid upon the bottom table member 8, and lined up with the edges thereof. The top table member 13 is then lowered into position, with the four pins 20 passing through the four hollow posts 11. The clamping members 26 are then placed in position and the apparatus 20 is ready for the use of the needle device shown in Figures 4 and 5.

25 The tufting needle device, or more than one, if it is desired that two or more persons work simultaneously on the mattress, is then taken in hand after a suitable length of tufting material has been threaded through the eyes 38, (leaving a long loop between them) and the two needles are placed in one of the slots 21, in the upper table member 13, whereupon the hand grip 29 is pushed downwardly. 30 The length of each slot 21 is substantially equal to the distance between the outer sides of the pair of needles 27 and 28, so that the needle device may be quickly placed in the proper position in the slot 21, and, at the same time, so centered that the needles pass through the mattress and come out the corresponding perforation or opening 12 in the lower table member 8, and symmetrically with respect to the center of such opening. The 35 needle device is then withdrawn, leaving the tufting material in the mattress.

40 The needle device is thus successively guided by the slots 21, after being re-threaded each time, and a half loop of tufting material appears on the upper side of the mattress, while the threaded-through or loose ends remain below the lower side of the mattress within the confines of each opening 45 12 in the lower table member. In other words, after suitable threading of the tufting material, the needle device is properly positioned with respect to a given slot 21, the hand grip is then pushed downwardly, and 50 the needles are then withdrawn by means of the hand grip, and the entire tufting needle device is carried over to the next slot 21, where the operation is repeated.

55 The peculiar shape of the slots 21, having enlarged centers, is adapted to permit either

a lengthwise stitch through the half loop, thus making a tuft, or to permit adding a regular round cotton tuft in the center, which may be sewed in position through the enlarged center opening of each slot 21.

70

To finish the tufting of the mattress, the four pivot locks 6 are moved out of operating position, the top and bottom table members with the mattress between them are rotated to an inverted position, and the threaded-through tuft ends, which appear in each hole 12, are then readily tied, sewed or tufted, as may be desired, without in any way disturbing the tufting table parts. It will be understood that to lock the table in such inverted position, the pivot locks 6 are again brought into play, to then grip the bottom table member 8 in its inverted position.

75

80

The pivot locks are then again removed, the table members and mattress rotated to normal position, the clamps 26 removed, and the top member 13 pulled upwardly, whereupon the finished mattress 25 may be removed and another one put in its place.

It will be seen, therefore, that I have provided a simple and inexpensive tufting table and needle assembly for producing quick and accurate tufting of a mattress, the tufts being symmetrically spaced apart, thus imparting a neat standardized appearance to the mattress. Furthermore, the illustrated needle device may be quickly and accurately employed, without requiring any great skill, and at the same time, if a needle breaks, the device may be very readily repaired with a minimum of disassembly and reassembly.

I do not wish to be restricted to the specific structural details or arrangement of parts herein set forth, as various modifications of my apparatus may be made without departing from the spirit and scope of my invention. I desire, therefore, that only such limitations shall be imposed thereon as are indicated in the appended claims.

I claim as my invention:

1. A tufting table comprising an upright frame, a perforated bottom member adapted to support a mattress, means for pivotally securing said member to said frame, means for locking said member in position, a removable perforated top member for laying on the mattress, means for positioning said top member with its perforations registering with the perforations in the bottom member, and a needle device for carrying a length of tape and adapted to be successively guided by the top member perforations through the corresponding bottom perforations, said locking means being also adapted to lock said bottom member in an inverted position when the top and bottom members and the mattress are rotated on said pivotal means to permit access to the threaded-through ends of tape.

115

2. A tufting table comprising an up-

120

125

130

135

140

right frame, a bottom member having spaced relatively large holes and adapted to support a mattress, means for pivotally securing said member to said frame, a plurality of locking devices pivoted on said frame for locking said member in position, a removable top member for laying on the mattress and having spaced relatively small slots, mutually engaging means on said members for positioning the centers of said slots substantially in alinement with the centers of said holes, and a plural needle device for carrying a length of tape and adapted to have its set of needles successively guided by said slots through the respective holes, said locking devices being also adapted to lock said bottom member in an inverted position when the top and bottom members and the mattress are rotated on said pivotal means to permit access to the threaded-through ends of tape.

3. A tufting table comprising an upright frame, a bottom board having regularly spaced relatively large holes, and adapted to support a mattress, means for pivotally securing said board to said frame, a plurality of locking devices pivoted on said frame for locking said board in position, a suspendable top board for laying on the mattress and having relatively small slots, male and female centering posts on said boards for positioning the centers of said slots substantially in alinement with the centers of said holes, and a device having two needles for carrying a length of tape and adapted to be successively guided by said slots through the respective holes, said locking devices being also adapted to lock said bottom board in an inverted position when the top and bottom boards and the mattress are rotated on said pivotal means to permit access to the various threaded-through pairs of ends of tape.

4. A tufting device comprising a needle, a hand grip at one end thereof, a guide block having a loose passage for said needle and initially located near the other end thereof, and a plurality of removable members placed on said block in juxtaposition to provide a substantially exact guide passage for said needle.

5. A tufting device comprising a pair of needles, a hand grip covering one end thereof, a guide block having loose passages for said needles, and initially located near the other ends thereof, and a plurality of removable members placed adjacent to each other on said block to provide close guide passages for the respective needles.

6. A tufting device comprising a needle, a hand grip at one end thereof, a guide block having a loose passage for said needle and initially located near the other end thereof, means attached to both said grip and said block for permitting the one to slide toward the other, and a plurality of removable mem-

bers placed on said block in juxtaposition to provide a substantially exact guide passage for said needle upon said grip and said block sliding the one toward the other.

7. A tufting device comprising a pair of needles, a hand grip covering one end thereof, a guide block having loose passages for said needles, and initially located near the other ends thereof, guide members extending between said grip and said block for permitting the grip to slide toward the block, and a plurality of removable members placed adjacent to each other on said block to provide close guide passages for the respective needles upon said grip sliding toward said block.

8. A tufting device comprising a pair of needles having enlarged points, a hand grip covering the blunt ends thereof, a guide block having loose passages for said needles and normally located in back of said points, a pair of guide members rigidly secured to said block and extending loosely through said grip for permitting the grip to slide along said members toward the block, and a set of three alined removable members on said block to provide close guide passages for the respective needles upon said grip sliding toward said block.

In testimony whereof, I have hereunto subscribed my name this 22 day of May, 1930.

HARRY E. WOLF.
